UNITED STATES PATENT OFFICE.

HIPPOLYT SAURER, OF ARBON, SWITZERLAND.

MACHINE FOR PUNCHING JACQUARD-CARDS.

1,104,551.

Specification of Letters Patent.

Patented July 21, 1914.

Application filed July 29, 1913. Serial No. 781,712.

To all whom it may concern:

Be it known that I, HIPPOLYT SAURER, a citizen of the Republic of Switzerland, residing at Arbon, Switzerland, have invented 5 new and useful Improvements in Machines for Punching Jacquard-Cards; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 In the punching of holes in jacquard cards for use in automatic embroidery machines it is necessary, in addition to the punching of holes by which the movements of the work frame are controlled, to punch also 20 holes by which special functions or individual operations, such, for example, as the throwing into and out of operation of the perforators, the festoon devices, the speed changing devices, etc., are controlled. A 25 hole or group of holes must be punched for the initiation of each of such operations and one for stopping it. Some of these special functions or individual operations are, however, of such a nature that they must not 30 take place at the same time. It is necessary therefore that a second special function or individual operation of this nature be not initiated before the first has been stopped. It is, however, difficult for the operator of 35 the machine to remember for the throwing in of which special functions or individual operations he has punched holes in the jacquard card and for the stopping of which of such special functions or individual 40 operations he must therefore punch holes. If he does not perform his work accurately breakage in the automat or jacquard mechanism may subsequently occur when embroidering is carried on under the control 45 of the card punched.

The object of the present invention is to provide controlling or indicating apparatus for machines for punching jacquard cards used in automatic embroidery machines by 50 means of which the card puncher is relieved of the necessity of remeasuring for the initiation of which of these special functions or individual operations there have been punched holes and is enabled to tell at 55 any time which special functions or individual operations are initiated according to

the card. This is effected by causing the necessary adjustments of the determining device for the special functions or individual operations to move a controlling device which retains the position to which it has been moved even when the said determining device has returned to its zero or normal position.

60 A form of apparatus constructed in accordance with the invention is illustrated in the accompanying drawings to which reference will now be had.

In the drawings—Figure 1 is a view partly in elevation and partly in section showing a portion of the pattern board of a machine for punching cards for use in automatic embroidery machines, together with the punching mechanism so far as it is involved in the present invention and the 70 controlling and indicating mechanism. Fig. 2 is a detail view in section and on a larger scale of the punching mechanism. Fig. 3 is a view in elevation and on a larger scale than that of Fig. 1 of the controlling and 75 indicating mechanism. Fig. 4 is a view in vertical section looking to the right hand in Fig. 3 and with the segment removed, the plane of section being mainly just to the left of the shaft 41, but partly to the 80 right of the shaft 21. Fig. 5 is a detail view in elevation of the punching mechanism as seen from the side opposite to that represented in Fig. 1. Fig. 6 is a detail view in horizontal section through the upper part 85 of the controlling and indicating mechanism shown in Figs. 3 and 4 and on a somewhat larger scale. Fig. 7 is a view in horizontal section of the controlling and indicating mechanism and on the same scale as Figs. 90 3 and 4, the plane of section being just above the axis of the shaft 21. Fig. 8 is a detail view in elevation of a portion of the controlling and indicating mechanism on the same scale as Figs. 3 and 4. Fig. 9 is a detail view in elevation of a portion of the 95 controlling and indicating mechanism on a larger scale than that of Figs. 3 and 4. Figs. 10 and 11 are detail views of a portion of the punching mechanism shown in Fig. 5 but on a larger scale. Fig. 12 is a detail view in horizontal section of a portion of the controlling and indicating mechanism on the same scale as Figs. 3 and 4. Fig. 13 is a detail view of the punch-selecting slide. Figs. 14, 15 and 16 are detail 100 views of some of the indicating disks.

K is the card punching apparatus, the devices for punching the holes which control the movements of the work frame being omitted.

5 M is the pattern board, the pantograph being removed, and C is the controlling and indicating apparatus.

In the card punching apparatus 1 is the strip of card to be punched, 2 are the perforating punches and 3, see Figs. 1, 2 and 13, is the device which determines which of the punches are in operation and comprises a slide the underside of which is formed with a number of recesses 4 so arranged that, 15 according to the position of the slide, certain of the four adjacent perforating punches 2 are caused to operate.

The perforating punches 2 are suspended in a punch carrier 5, see Fig. 2, which can 20 be vertically reciprocated by a system of links and levers 6 and 7. The levers 7 are mounted upon a shaft 8 upon which is fixed a lever 9, see Fig. 5, the free end of which is furnished with a roller 10 which works in 25 the groove 11 of a cam 12 fast on a shaft 13 that is driven in any suitable manner by a chain wheel 14. When the carrier 5 is lowered those punches 2 above which are located recesses 4, see Fig. 13 merely rest 30 upon the strip of card 1 and do not punch any hole therein, but those punches 2 above which there are no recesses 4 punch holes in the card. When the recesses 4 along the line A—B in Fig. 13 lie above the four punches 35 2 the slide 3 is in the zero or normal position and none of the four punches 2 punches a hole in the card when the carrier 5 descends. Attached to the slide 3, see Figs. 1 and 2, is one end of a link 15 the other end 40 of which is attached to a lever 16 fixed on a shaft 17. Upon the shaft 17 is fixed a chain wheel 18 which is in driving connection by means of a chain 19 with a chain wheel 20 on the controlling and indicating apparatus 45 C, see Figs. 1, 2, and 7.

The chain wheel 20 is fixed upon a shaft 21 upon which is also fixed a toothed segment 22 from which lever 24 projects laterally through a slot in the casing 23. The 50 slide 3 can therefore be readily shifted by moving the lever 24.

The card punching apparatus is such as to enable an interrupted and an uninterrupted operation to be effected, the former 55 in such-wise that after each punching movement the chain wheel 14 can be stopped by means which are not shown. The slide 3 must be returned to its zero or normal position during the movement of the wheel 14. 60 This is effected by a disk 25, see Figs. 5, 10 and 11, provided with two lugs or projections 26, 27 having oppositely directed guide paths or surfaces 28. The disk 25 is fixed upon the shaft 13.

65 Guided between rollers 30 on the side

shield or frame 29 is a rod 31 projecting vertically from which is an arm 32 the upper end of which is furnished with a roller 33 the diameter of which is such that it can pass between the two lugs or projections 26 70 and 27.

The rod 31 is formed at one part of its length with teeth 34 meshing into a toothed segment 35 fast on the shaft 17, see Figs. 2 and 5. If therefore the slide 3 be moved by 75 the rotation of the shaft 17 for the purpose of adjusting it the rod 31 will also be moved whereby for example the roller 33 will be caused to assume a position with relation to the lugs or projections 26 and 27 such as 80 shown in Fig. 10. If the shaft 13 then makes an operative rotation the disk 25 will also rotate and one of the lateral guides or surfaces 28, see Fig. 10, will force the roller 33 into the central position whereby the 85 shaft 17 will be rotated backwardly and the slide 3 and the lever 24 will be brought into their normal or zero positions in which they are shown in Fig. 1. The lever 24 occupies this position when the only holes to be 90 punched are those which control the movements of the work frame and therefore of the fabric.

The toothed segment 22 which is rigidly connected to the lever 24 gears into a rack 95 36, see Fig. 7, which is mounted to move vertically between rollers 37. Attached to this rack, see Fig. 4, is a fork 38 which loosely embraces a driver 39 which is provided with two lateral arms 40, see Figs. 7 100 and 6, and is arranged to move axially upon a shaft 41 of square cross section. This shaft is mounted to rotate in bearings at its top and bottom and near its lower end it has fixed on it a disk 42, Figs. 4 and 12, formed 105 with two notches 43.

44 is a gear wheel mounted to rotate freely upon a round portion of the rod 41 and having rigidly connected to it an arm 45 on which is mounted a spring pressed pawl 46 110 adapted to engage the notches 43 of the disk 42. Meshing with the wheel 44 is a toothed segment 47 which is mounted to rotate about a fixed pin 48 and to which is connected one end of a connecting link 49, see Figs. 1, 5 115 and 7, the other end of which is connected to a lever 50 which receives its motion from a cam 66 on the shaft 13. By means of this mechanism the driver 39 is rotated step by step in one and the same direction. Upon a rod 51 arranged parallel with the shaft 41 in the controlling and indicating apparatus C, see Figs. 4, 6, 7, 8 and 9, 14, 15 and 16, are arranged to rotate freely but not to move axially, disks such as 52', 52" which act as 120 controlling or indicating devices. Certain of the disks such as 52', 52" have at the top four pins 53, see Figs. 14, 16 and other six pins, see Fig. 15.

Rigidly connected to the rack 36 is a 130

pointer 54 which moves over a scale 55. The arrangement is such that if the lever 24 be so moved that the pointer 54 is placed over a particular division of the scale the driver 39 is compelled to assume such a position that when it is rotated one of the arms 40 causes the corresponding one of the indicating disks such as 52^t, 52^p to rotate through a fourth or a sixth of a rotation according to whether it has four or six pins 53.

The peripheries of some of the disks such as 52^t, 52^p are provided with red and white areas and some of them, as hereinafter explained, are provided with teeth. When a disk is rotated there will consequently appear at a window 56 in the casing of the controlling or indicating apparatus a red mark or a particular number as will be more fully explained hereinafter. To the topmost disk 52^t, see Fig. 9, is rigidly connected a toothed wheel 57 which gears into two gear wheels 58 and 59. The gear wheel 59 rotates freely upon a fixed shaft 60 and is rigidly attached to a number disk 61. The gear wheel 58 rotates freely upon a fixed spindle 62 and is rigidly connected to a disk 52^a which has four pins 53. The lowermost number disk 52^c, see Figs. 4 and 8, is rigidly connected to a toothed wheel 63 which gears into a toothed wheel 64 to which a disk 52^e is connected.

The action of the apparatus is for example as follows: When holes are being punched which cause movement of the work frame the pointer 54 will be opposite the mark "Embroidery" and the slide 3 will be in its zero or normal position. Supposing now holes are to be punched which subsequently initiate the throwing into operation of the festooning devices in the automatic embroidering machine, the lever 24 will be pushed upwardly until the pointer is opposite the mark "Festoon." This causes the slide 3 to be correspondingly adjusted and at the same time the driver 39 to be raised to such a height that its arms 40 are brought on a level with the pins 53 of the disk 52^t. If now the driving mechanism of the card punching apparatus be thrown into operation holes in the card corresponding to festooning will first be punched and the link 49 and the segment 47 will rotate the rod 41 and consequently the driver 39, whereby the disk 52^t will be rotated so that, as intended to be indicated in Fig. 3, a red area thereof will appear behind the window 56. On the return of the slide 3 to its zero or normal position the lever 24 will also be returned to the position shown in Fig. 3 but the controlling disk 52^t will not be rotated further but will retain its position. Other special functions or individual movements can now be initiated. Thus for example if the pointer 54 be set opposite the mark "Depth of perforation" + the driver 39

will rotate the controlling disk 52^t, see Fig. 9, whereby the gear wheel 57 will be rotated and with it the gear wheel 59 and consequently also the number disk 61 so that the fixed pointer 65 will now point to "3" instead of "2," see Fig. 3. If however the pointer 54 be set opposite the mark "Depth of perforation" — the driver 39 will rotate the disk 52^a whereby the number disk 61 will be rotated in the opposite direction by the gear wheels 58, 57, 59, so that then the pointer 65 would point to "1" instead of "2". If the card puncher then desires to so punch the card that the festooning instruments shall be again thrown out of operation thereby he must punch holes by means of which the initiated movements of the festooning instruments shall be again stopped. That this is necessary the card puncher can readily see from the red mark on the controlling disk 52^t. He then sets the pointer 54 again opposite the mark "Festoon" and punches the necessary holes. This causes the controlling disk 52^t to again be rotated by the driver 39 so that a white area appears behind the window and indicates that the perforations for the stoppage of the operations of the festooning instruments have been punched. The card puncher has therefore always before him what interpolated perforations he has made for special functions or individual operations and to stop which he must punch certain holes before he punches holes for initiating other special or individual operations which might otherwise result in damage in the automaton. When the card is completely punched the controlling and indicating apparatus should for example not exhibit any red areas.

I claim:

1. In a machine for punching jacquard cards, the combination of a punch-selecting device, means for operating said device, an indicating device and transmitting mechanism whereby the indicating device is moved to a position of rest with the movement of the selecting device.

2. In a machine for punching jacquard cards, the combination of a punch-selecting device, selective means for shifting said device to different positions, a series of indicating devices corresponding to the several positions of the punch-selecting device, a driver adapted to be moved with the movement of said shifting means into operative relation with the corresponding indicating device, and transmitting mechanism whereby the driver is actuated with the movement of the selecting device.

3. In a machine for punching jacquard cards, the combination of a punch-selecting device, selective means for shifting said device to different positions, a series of indicating disks, a shaft parallel with the series

- 4 of disks and adjacent thereto, a driver mounted to slide on said shaft and to rotate therewith and adapted to engage operatively one or another of said disks, connections whereby the driver is shifted by the operation of the selective means into operative relation with one or another of said disks, and transmitting mechanism whereby the shaft is actuated with the movement of the punch-selecting device.
- 5 4. In a machine for punching jacquard cards, the combination of a punch-selecting device, selective means for shifting said device to different positions, an indicating disk, a transmitting disk reversely geared to the first disk, a driver adapted to be moved with the movement of said shifting means into operative relation with the first named disk or with the transmitting disk, and 10 transmitting mechanism whereby the driver is actuated in one direction with the movement of the selecting device.
- 15 5. In a machine for punching jacquard cards, the combination of a punch-selecting device, selective means for shifting said device to different positions, an indicating disk, a transmitting disk reversely geared to the first disk, a shaft parallel with the axes of said disks and adjacent thereto, a 20 driver mounted to slide on said shaft and to rotate therewith and adapted to engage operatively either the indicating disk or the transmitting disk, connections whereby the driver is shifted on the shaft by the operation of the selecting means into operative relation with one or the other of said disks, and transmitting mechanism whereby the shaft is actuated with the movement of the punch-selecting device.
- 25 6. In a machine for punching jacquard cards, the combination of a punch-selecting device, selective means for shifting said device to different positions, a series of indicating disks, a shaft parallel with the series 30 of disks and adjacent thereto, a driver mounted to slide on said shaft and to rotate therewith and adapted to engage operatively one or another of said disks, a rack operatively connected with the driver to shift
- 35 the same on the shaft, a gear segment engaging said rack and operatively connected with the selecting means, and transmitting mechanism whereby the shaft is actuated with the movement of the punch-selecting device.
- 40 7. In a machine for punching jacquard cards, the combination of a punch-selecting device, selective means for shifting said device to different positions, a series of indicating disks, a shaft parallel with the series 45 of disks and adjacent thereto, a driver mounted to slide on said shaft and to rotate therewith and adapted to engage operatively one or another of said disks, a ratchet wheel on said shaft, an actuating pawl for said ratchet wheel, a gear carrying said pawl, a segment engaging said gear, and transmitting devices whereby the segment is actuated with the movement of the punch-selecting device.
- 50 8. In a machine for punching jacquard cards, the combination of a series of punches, actuating devices therefor, a punch-selecting slide, an indicating device, and transmitting mechanism whereby the indicating device is moved to a position of rest with the movement of the slide.
- 55 9. In a machine for punching jacquard cards, the combination of a series of punches, actuating devices therefor, a punch-selecting slide, a series of indicating devices corresponding to the several positions of the punch-selecting slide, a driver adapted to be moved with the movement of the slide into operative relation with the corresponding indicating devices, and transmitting mechanism whereby the driver is actuated in one direction with the movement of the slide.
- 60 90 In testimony that I claim the foregoing as my invention I have signed my name in presence of two subscribing witnesses.

HIPPOLYT SAURER.
